[57] ABSTRACT

A cymbal attachment includes a fixed bracket secured to the cymbal mounting bolt, and a second bracket secured to the fixed bracket. The second bracket supports a number of spring arms having weighted cymbal engaging ends. In one position the weighted arm ends engage the cymbal surface, and in another position the arm ends are held spaced from the cymbal surface in inoperative position.

CYMBAL ATTACHMENT

This invention relates to an improvement in sizzler and deals particularly with a cymbal attachment designed to produce a new and unusual sizzle like sound.

BACKGROUND OF THE INVENTION

Devices known to the musical trade as sizzlers have been produced for a number of years. These devices vary considerably in design, and also in tonal effect. For example, many cymbals have been produced having rivets extending loosely through holes in the edges of the cymbals, these rivets vibrating when the cymbal is struck so as to produce a sound which is considerably different from that produced by an unmodified cymbal. Other such cymbals have been produced by loosely mounting washers or other forms of discs near the periphery of the cymbal, these also producing what is known as a sizzling sound when the cymbal is struck. Other modifications of such devices have also been employed which vary considerably in design, and also vary somewhat in sound.

Cymbals of this type have the disadvantage that they only serve a single purpose. In other words, the cymbal will not produce the customary cymbal sound, and may only be used when a sizzling effect is desired. This requires that such a cymbal be used in addition to the conventional cymbal, adding to the already bulky equipment normally used by a drummer, and requiring additional space available to the drummer. This tends to cause difficulty, particularly where the available stage or platform is of relatively small size.

Certain attempts have been made to provide effective sizzler attachments which may be secured to a conventional cymbal. One such attachment includes a pair of pivotally supported arms mounted on a hub coaxial with the cymbal and having inverted cup shaped elements designed to rest upon the surface of the cymbal. One of the disadvantages of this type of construction lies in the fact that the sizzling effect is somewhat limited by the fact that only two such devices are provided. These devices may be pivoted into or out of engagement with the surface of the cymbal to permit conventional use of the cymbal when desired. However, as the arms supporting the sizzler devices must be individually pivoted, time is required to swing the arms into or out of operative position. If the number of sizzling attachments is increased, this correspondingly increases the time and effort required to pivot the supporting arms.

SUMMARY OF THE INVENTION

An object of the present invention resides in the provision of a sizzler which is an attachment to a cymbal, but which may be moved into or out of cymbal engaging position with a single swift movement. The device may be moved from inoperative position to operative position, or vice versa, by a single movement of a drumstick or finger. Thus, the device may be put into or out of operative position without interrupting the rhythm of the drummer.

A further feature of the present invention resides in the provision of a device of the type described including a supporting bracket which supports a plurality of light weight resilient arms. These arms are arranged to vibrate independently of one another so as to provide an unusual tonal effect when the cymbal is struck.

A further feature of the present invention resides in a device of the type described in which the springs are provided with weighted ends which engage the surface of the cymbal. As a result, as the cymbal is set into vibration, the springs are in turn vibrated providing an effect which is sustained longer than with most previous devices. The springs are sensitive to a very light touch and also to a very heavy touch, permitting a variety of effects to be attained.

A further feature of the invention resides in the fact that the attachment leaves the center bell of the cymbal clear for special effects on this portion of the cymbal. Some drummers use this center bell to produce unusual effects when struck with a

drumstick, and the present attachment does not interfere with this operation.

An object of the present invention resides in the provision of a cymbal attachment having a first bracket portion which may be adjustably mounted on the center bell of the cymbal, and a second bracket which is pivotally secured to the first bracket on a generally horizontal axis. The structure is such that the sizzler may extend in any direction from the bell to suit the convenience of the drummer. The thin spring sizzler arms are connected to the second bracket portion and support weighted ends which move into or out of engagement with the surface of the cymbal depending upon the pivotal position of the second bracket relative to the first. In preferred form, the second bracket is held in inoperative position by simple means such as a permanent magnet mounted on the second bracket for engagement with the first bracket when the sizzler arms are raised. When in operable or cymbal engaging position, the magnet is moved away from the first bracket arm and toward an adjustment screw which limits the relative swinging movement between the two brackets.

An added feature of the present invention resides in the provision of a device of the type described which is simple to produce. The spring strips individually extend through slots in a reversely turned flange on one edge of the second bracket and are clamped in place by ears struck from the body of the second bracket. The cymbal engaging means comprise small metal balls such as bearings which are held to the arms by simple loop shaped clips. The two brackets are pivotally connected by means of a pivot member which serves both as a pivot and as a handle by means of which the second bracket may be pivoted.

A further feature of the present invention resides in the fact that the elevation of the weighted ends of the spring arms may be adjusted by an adjustment screw. With this arrangement, considerably different effects are available. By supporting the weighted ends of the sizzler arms slightly out of contact with the cymbal, a different effect may be accomplished over that obtained when the full weight of the second bracket and the sizzler arms are resting upon the surface of the cymbal. Furthermore, this construction is such that the sizzler arms may be quickly disengaged from the cymbal surface at any time so as to immediately stop the sizzling effect. The ability to immediately stop the sizzling action when desired is novel and permits a wide variation of additional effects to be obtained.

These and other objects and novel features of the present invention will be more clearly and fully set forth in the following specification and claims.

BRIEF DESCRIPTION OF THE DRAWINGS

FIG. 1 is a perspective view of a cymbal with the sizzler attachment mounted thereupon.

FIG. 2 is a side elevational view of the cymbal and attachment.

FIG. 3 is a top plan view of the attachment in enlarged form.

FIG. 4 is a side elevational view of the attachment as indicated in FIG. 3.

FIG. 5 is a bottom plan view of the attachment removed from the cymbal.

FIG. 6 is a perspective view in enlarged form showing the end of one of the spring arms.

FIG. 7 is an end elevational view of the spring arm illustrated in FIG. 6.

FIG. 8 is a side elevational view of the arm end shown in FIG. 6.

FIG. 9 is an enlarged bottom plan view of a section of the second bracket indicating the manner in which the spring arms are attached.

FIG. 10 is a detailed sectional view, the position of the section being indicated by the line 10-10 of FIG. 9.

DESCRIPTION OF THE PREFERRED EMBODIMENT OF THE INVENTION

The cymbal A illustrated in FIGS. 1, 2 and 4 of the drawings is of conventional form, and may vary somewhat in shape and size. In general, the cymbal comprises a disc 10 having a concave undersurface and a convex upper surface. An upwardly domed bell portion 11 is provided at the center of the disc 10. A bolt 12 extends upwardly through the center of the dome shaped portion 11 and is encircled by a nut 13 designed to permit a desired amount of movement in the cymbal. A wing nut 12a is normally mounted upon the bolt 12 to hold the cymbal A in position upon a suitable support 13 from which the bolt 12 extends. In view of the fact that the cymbal as well as the cymbal supporting means is well known in the art, this arrangement is not indicated in any detail.

The cymbal attachment is indicated in general by the letter B, and includes a first bracket 14 and a second bracket 15 which are pivotally connected in a manner which will be described. The bracket 14 comprises an elongated strip 16 of metal or other suitable material including apertures 17 designed to accommodate the cymbal mounting bolt 12. The strip 16 is transversely curved or arcuated as indicated at 19 to form a bearing for the pivot which will be described. The extremity of the arm inclines upwardly and rearwardly relative to the end of the strip containing the aperture 17. This upwardly inclined portion 20 terminates in an offset end portion 21 which includes a threaded aperture to accommodate an adjustment bolt 22. A spring 23 preferably encircles the bolt 22 and extends between the arm end 21 and the bolt head 24 to hold the adjustment bolt from rotation due to vibration or the like.

The bracket portion 15 comprises a generally trapezoidal sheet or plate of flat metal or the like as indicated at 25 having a reversely turned flange 26 (see FIGS. 5 and 9) which extends generally parallel to the trapezoidal body 25 and which is connected thereto along the longer parallel edge of the trapezoidal plate. The folded edge 27 connecting the plate edge of the plate 25 and the flange 26 is apertured at spaced intervals as is indicated at 29. A series of spaced spring fingers or arms 30 extend through the apertures 29 and are anchored against the under surface of the plate 25 by opposed pairs of ears 31 indicated in FIGS. 9 and 10 of the drawings. The pairs of ears 31 are spaced at varying distances from the folded edge 27 connecting the plate 25 to the flange 26. As a result, even though the spring arms 30 may be of equal length, the portions of the arms which project beyond the folded edge 27 of the bracket 15 may be varied. In the particular arrangement illustrated, eight such arms are provided, four of which project substantially beyond the ends of the remaining four arms. Obviously, however, the number of arms may be varied, and the length of the arms may also be varied quite materially. The arms 30 extend in outward divergent or fan-shaped relation.

The bracket 15 is supported by a pair of parallel arms 33 having hook-shaped ends 34 which engage over the folded edge 27. The arms 33 are provided with ears 35 which extend through apertures in the plate 25 (see FIG. 5) and are bent or deformed to securely clamp the plate to the arms. The arms 33 project well beyond the supporting plate 25, and are properly spaced to straddle portions of the bracket strap 16.

As is indicated in FIGS. 3 and 5 of the drawings, a U-shaped handle 36 has an arm 37 which extends through intermediate portions of the parallel arms 33 and through the bearing provided by the loop shaped portion 19 of the bracket 14. The arm 37 of the U-shaped member 36 thus forms a pivotal connection between the brackets 14 and 15. The other parallel arm 39 of the U-shaped bracket 36 extends through apertures in the extremities of the arms 33 which are most remote from the hook shaped ends 34. The ends of the U-shaped handle 36 and other portions of the arms 37 and 39 may be upset or enlarged slightly to hold the handle in place. The U-shaped handle thus pivots with the bracket portion 15 and may be engaged by a drumstick or by a finger to pivot the bracket B from one extreme position to another.

An inverted channel 40 extends transversely between the arms 33 near the leg 39 of the handle 36. The channel 40 is provided with projecting ears 41 which extend through the arms 33 to hold the channel in place. The channel 40 includes a permanent magnet 42. The bracket 14 is made of magnetic material so that the magnet 42 is capable of holding the bracket B with the spring arms 30 in an elevated position as indicated in FIG. 4 of the drawings. However, when manually pivoted to the other extreme position indicated in dotted outline in FIG. 4 of the drawings, the magnetic field is not sufficiently strong to swing the bracket 15 back into its inoperative position.

The ends of the arms 30 preferably support metal balls 43 which are adapted to strike the surface of the cymbal A. End portions of the arms 30 are preferably upwardly bowed as indicated at 44 to generally fit the curvature of the upper surface of the ball 43. A generally rectangular loop 45 is bent into U-shaped form, the ends 46 of the loop extending over the arm 30 on opposite sides of the upwardly bowed portion 44, and the intermediate portions thereof looped downwardly as indicated at 47 to engage against the sides of the ball 43 beneath the center thereof. The ends 49 of the arms 30 are then bent upwardly to hold the parts assembled. When assembled the loops 45 support the balls 43 in the manner illustrated in the drawings.

The attachment B, when in use, is mounted upon the cymbal supporting bolt 12, and held in place by the cymbal supporting nut 12a. The resilient arms 30 on the supporting bracket 15 may be pivoted relative to the bracket 14 which is held in fixed position. When in lowered position, as the cymbal A is struck with a drumstick or the like, the ball ends 43 of the spring arms 30 vibrate against the surface of the cymbal and produce an extremely effective sizzling sound. Due to the fact that the weighted ends of the weighted end 43 are mounted upon thin resilient arms 30, the sizzling sound is maintained long after the cymbal is struck. At the same time, the weighted ends 43 may be immediately withdrawn from the surface of the cymbal by merely pivoting the bracket portion 15 out of engagement with the cymbal. When in raised position, the bracket is held inoperative by the magnet 42. The channel 40 serves the double purpose of enclosing the magnet 42, and also as a stop for limiting the pivotal movement of the bracket B by engagement with the adjustment bolt 22.

In accordance with the Patent Statutes, I have described the principles of construction and operation of my sizzler attachment and while I have endeavored to set forth the best embodiment thereof, it should be understood that obvious changes may be made within the scope of the claims without departing from the spirit of my invention.

We claim:

1. A cymbal attachment including:
a first bracket having an aperture for attachment to a cymbal support,
a second bracket pivotally connected to the first bracket for swinging movement toward and away from the cymbal,
a series of resilient arms supported at one end by said second bracket and extending in a direction away from the cymbal support, and
weighted ends on the other ends of said resilient arms.
2. The structure of claim 1 and including releasable means holding said second bracket in its position away from said cymbal.
3. The structure of claim 2 and in which said releasable means includes a magnet on one of said bracket engageable with the other bracket when said second bracket is in its position away from said cymbal.
4. The structure of claim 1 and in which said resilient arms comprise flat strips of resilient material.
5. The structure of claim 1 and including adjustable means for limiting the pivotal movement of said second bracket toward said cymbal.
6. The structure of claim 1 and in which said weighted ends comprise balls engageable with the cymbal surface.

7. The structure of claim 6 and including generally rectangular loops having ends overlying said arms, and having intermediate generally U-shaped portions engaging said balls.
